UNITED STATES PATENT OFFICE

108,056

DESIGN FOR A DRESS

Sidney J. Poster, New York, N. Y.

Application December 8, 1937, Serial No. 73,454

Term of patent 3½ years

To all whom it may concern:

Be it known that I, Sidney J. Poster, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the appliques of printed fabric and netted stems on the waist section, in combination with the dress as shown.

I claim:

The ornamental design for a dress, substantially as shown, and described.

SIDNEY J. POSTER.
